(57) CLAIM

The ornamental design for a holiday boot cork holder, as shown and described.

DESCRIPTION

FIG. 1 is a front perspective view of a holiday boot cork holder showing my new design;

FIG. 2 is a rear perspective view thereof;

FIG. 3 is a top view thereof;

FIG. 4 is a side view thereof; and,

FIG. 5 is a bottom view thereof.

The broken lines depict portions of the holiday boot cork holder that form no part of the claimed design.
